By Henry S. Peltier
Attorney,

UNITED STATES PATENT OFFICE.

PETER CLOSS, OF WOLLASTON, ASSIGNOR OF ONE-HALF TO JOHN W. SAN-BORN, OF BOSTON, MASSACHUSETTS.

BOOK-COVER.

SPECIFICATION forming part of Letters Patent No. 444,376, dated January 6, 1891.

Application filed February 8, 1890. Serial No. 339,746. (No model.)

To all whom it may concern:

Be it known that I, PETER CLOSS, a citizen of Massachusetts, residing at Wollaston Heights, in the county of Norfolk and State of Massachusetts, have invented certain new and useful Improvements in Book-Covers; and I do hereby declare the following to be a full, clear, and exact description of the invention, such as will enable others skilled in the art to 10 which it appertains to make and use the same.

My invention relates to an improvement in the method of attaching the clamp to the recessed back of the book-cover. Heretofore the said clamp has been attached to the recessed back and covers by a piece of cloth fastened to said clamp by points or prongs bent or clinched to said cloth or without said points or prongs, and then said cloth is pasted to said covers and back. This requires stock, 20 time, and labor. I have accomplished my purpose by avoiding the use of any cloth or any points or prongs and fastening said clamp directly to said recessed back by eyelets clinched at the end, thus saving stock, time, 25 and labor. This method of fastening holds the clamp firmly in the recessed back without interfering with the insertion or removal of said memorandum-book into or out of said clamp. The said clamp has divergent 30 corners and is inserted into said recessed back. The memorandum-book slides into and out of the said clamp, which grasps and holds said book, and said book can only move in the direction of the length of said back.

35 In the drawings, Figure 1 is a perspective view of the entire memorandum-book with one cover thereof raised. Fig. 2 is a longitudinal edge view of the same. Fig. 3 is an end view with the book removed, and Fig. 4

is a partial longitudinal section enlarged 40 through the place where a rivet is located.

A represents the book; B, the clamp, in which the edge of said book is inserted directly or without any intermediate means; b, the fastening; C, the back; D D, the covers. 45 My method of attaching said clamp to the recessed back of said cover is as follows: I make a round perforation or perforations at about the end or ends of said clamp, as shown in the drawings, using a common eyelet-machine of the size of the eyelet used. Then inserting the eyelet or eyelets I compress the end, fastening the eyelet or eyelets firmly in place, leaving no edge to interfere with the insertion of said book. 55

Having described my invention, what I claim is—

The combination, with the covers D and back B, said back having a perforation or perforations, of a substantially V-shaped 60 clamp having a perforation or perforations in its rear end registering with the perforation or perforations in said back, an eyelet or eyelets passing through said perforation or perforations in said back and clamp and 65 securing the same together, said eyelet or eyelets having clinched ends, and the removable book A, having its rear end inserted directly into said clamp and its sides at said end in close contact with the inner surfaces 70 of the sides thereof.

In testimony whereof I affix my signature in presence of two witnesses.

PETER CLOSS.
